UNITED STATES PATENT OFFICE

EDWARD W. BURGESS, OF MILWAUKEE, WISCONSIN, ASSIGNOR TO A. O. SMITH CORPORATION, OF MILWAUKEE, WISCONSIN, A CORPORATION OF NEW YORK

FLOOR OR PAVEMENT AND METHOD OF PRODUCING THE SAME

Application filed June 6, 1928. Serial No. 283,156.

The invention resides in the provision of a metal grid of novel and improved construction adapted to be incorporated in a floor or a pavement to enhance the quality of the wearing surface thereof.

The general nature of my invention having thus been briefly stated, I shall now proceed to fully describe the features and characteristics thereof, and shall later specifically point out the novelty of the invention in claims hereto appended.

In the accompanying drawings forming a part of this specification,

Fig. 1 is a plan view of a fragment of a blank of sheet metal from which a grid having the features of the invention can be produced, there being holes through the said blank of sheet metal. The punching of the holes may desirably constitute the first operation in the production of the metal grid.

Fig. 2 is a fragmentary sectional view of a set of tools for forming cups upon the blank of sheet metal about the holes, disclosing a fragment of the blank as when acted upon by the tools. The cupping of the blank may desirably constitute the second operation in the production of the grid.

Fig. 3 is a fragmentary plan view disclosing the blank after portions thereof have been cut away to leave connecting webs between the cups, and tongues about the bases of the cups and between the different connecting webs. The cutting away of portions of metal between the cups may desirably constitute the third operation in the production of the grid.

Fig. 4 is a view similar to Fig. 3, but disclosing the tongues about the bases of the cups and between the different connecting webs as having been bent downwardly, in direction away from the connecting webs opposite that in which the cups extend. The bending of the tongues may desirably constitute the fourth operation in the production of the grid.

Fig. 5 is a fragmentary elevational view of a set of tools for so bending down the tongues, disclosing a fragment of the blank as when acted upon by these tools.

Fig. 6 is a fragmentary sectional view of

a set of tools for sizing the cups to dispose their free edge faces in a single plane, and for causing the said free edge faces to be thickened in case thicker edge faces are in a particular instance desirable. The sizing or leveling of the cups may desirably constitute the final operation in the production of the grid.

Fig. 7 is a fragmentary plan view, on a somewhat larger scale, disclosing a plurality of the grids and an interlocking device applied to align the grids both vertically and horizontally.

Fig. 8 is a fragmentary sectional view of a grid as it would appear on either line 8-8 in Fig. 7, the interlocking device being omitted.

Fig. 9 is a sectional view on line 9-9 in Fig. 7, detailing an interlocking device and its relation to the grids.

Fig. 10 is a perspective view, on a smaller scale, of a fragment of a floor or pavement having an incorporated grid (or grids) made in accordance with the principles of the invention, parts being sectioned and broken away to better disclose the structure.

Fig. 11 is a dotted line plan view diagrammatically disclosing the arrangement of the grids of Fig. 7.

Fig. 12 is a plan view of a modified form of grid having the features of the invention, disclosing, in dotted lines, several of the tongues before bent downwardly.

With more especial reference to Figs. 7 to 10, inclusive, of the drawings, I have there shown a metallic grid 20 which consists, generally, of a base-plate 21 having thereon upwardly extending, preferably perpendicular, filler receiving cups 22 and downwardly extending, preferably perpendicular, projections or lips 23. The body of the base-plate desirably has openings 24 therethrough of such dimensions that the base-plate is constituted by webs 25 spacing apart annular members 26 about and integral with the bases of the cups 22 to unite the whole in an integral structure.

Actually, the webs 25 could connect directly with the bases of the cups 22 so that the downwardly extending projections or lips 23 would be upon the bases of the

55

100

cups, instead of upon the annular members 26, as will be apparent.

The grid as briefly described could be a casting, but I desirably construct it from a blank of sheet metal, preferably sheet steel, in about the manner as now to be set forth.

In Fig. 1 there is disclosed a fragment of a blank of sheet metal 27 suitable for the manufacture of my grid. The punching of holes 28, at uniform and suitable distance apart, in the blank may constitute the first operation in the production of the grid. As shown, the holes are in parallel rows, and the holes of adjacent rows are in staggered relation.

After the holes are punched, the cups 22, consisting of metal about the holes desirably set at right-angles to the plane of the blank of sheet metal, may be formed in any convenient manner. In Fig. 2 there is disclosed a set of tools for accomplishing the cupping of the blank, the said set of tools consisting of ordinary punches 29 adapted to cooperate with ordinary dies 30 suitable to my purpose.

25 A fragment of the blank as when acted upon by the punches and dies is designated 31. The cups are so drawn that as much metal will be disposed therein as is consistent with the use for which the grid is designed.

30 The next operation in the production of the grid may consist in cutting away portions of metal between the cups, as indicated at 32 in Fig. 3. As shown, the cut-away parts 32 are of general triangular or clover shape, to leave the annular members 26 about the bases of the cups, the webs 25 between the different annular members, and a plurality of inwardly projecting extensions or tongues 33, three for each cut-away portion as shown, about 40 the annular members and in the plane of the blank of sheet metal. Any ordinary or preferred type of tool can be utilized to remove the parts 32 from the blank of metal.

The next operation may consist in bending 45 the extensions or tongues 33 downwardly to provide the projections or lips 23, desirably set at right-angles to the plane of the blank of sheet metal, as disclosed in Figs. 4 and 5. In Fig. 5, a set of tools suitable for 50 bending the extensions or tongues downwardly is designated 34, and a fragment of the blank of sheet metal after acted upon by these tools is represented 35 in Figs. 4 and 5. The projections or lips 23 are desirably of 55 the same length to be disposed in a single plane parallel with and beneath the plane of the webs 25 and annular members 26. Preferably, the lower edge faces of the said projections or lips 23 are flat, in order that the 60 finished grid can rest squarely upon a surface to be paved, as will be understood.

The final operation in the production of the grid may consist in sizing the cups to dispose their upper or free edge faces in a 65 single plane above the plane of the webs and

annular members and parallel therewith, and the sizing of the cups can be accomplished to cause the said free edge faces thereof to be materially thickened should relatively thick upper edge faces in a particular instance be desirable. In Fig. 6 I have disclosed a set of tools including a base 36 upon which the blank 37 is adapted to rest during the sizing operation, and a sizing die 38 adapted to engage the edge faces 39 of the cups to cooperate with the base 36 to accomplish the sizing. The blank is located for the sizing operation by means of pins 40 upon the base and passing upwardly through the cups and into openings of the sizing die. Any other set of tools suitable for accomplishing the desired result can be substituted for the set of tools disclosed.

The sequence of the operations as above set forth could be varied, or several of the operations might be combined, within the spirit of the invention.

In Fig. 12 I have disclosed a metal grid in all respects similar to the grid as already described, except that the arrangement of the cups is different and the cut-away portions between the cups are of modified shape. As here shown, the spaced apart cups are parallel in two directions, the cut-away portions are of general square configuration and are bounded by four cups and four webs instead of by three cups and three webs as in the form of the invention disclosed in Figs. 1 to 10, and there are four downwardly extending projections or lips 23 for each cut-away portion.

A fragment of a floor or pavement, having an incorporated grid (or grids) made in accordance with my invention, is disclosed in Fig. 10. The grid can be incorporated in the floor or pavement after any preferred or well known fashion. I may place the grid upon a foundation to be paved, and pour any suitable filler thereon until the filler is about flush with the upper edge faces of the cups of the grid, or I may similarly cast the grid integral with a slab suitable for a floor or pavement.

In order that no sharp edges will be present at the surface of the filler, or will protrude above the surface, I make certain that all of the upper or free edge faces of the cups lie in a single horizontal plane which is parallel with the body of the blank of sheet metal.

In Figs. 7 and 9 I have disclosed a plurality of grids each having the features of the invention, and interlocking devices, denoted 41, applied to the grids to align them both vertically and horizontally. One way in which I associate the grids with each other before applying the interlocking devices is best disclosed in Figs. 7 and 11, and I utilize as many or as few of the interlocking devices

as may be deemed desirable in a particular instance.

Each interlocking device 41 consists of a strip or piece of metal, preferably flat sheet metal, including arc shaped end portions 42 connected by a bridge piece 43, and spaced apart downwardly projecting ears 44 upon the lower edge of each of the arc shaped portions and having oppositely extending flanges 45 which provide, together with the ears, oppositely disposed hooks. The arc shaped portions 42 are adapted to partially envelope adjacent cups 22 of contiguous grids to be connected so that the bridge piece 43 lies between the cups in about the manner as best disclosed in Fig. 7, and the oppositely disposed hooks are adapted to fit about webs adjacent the corresponding cups in about the manner as best disclosed in Fig. 9.

The dotted line interlocking device of Fig. 7 is disclosed situated ready to be moved into its interlocking relation with respect to the adjacent grids there shown. The lower edge of the said device is in close proximity to the plane of the upper faces of the webs, and the ears and oppositely extending flanges constituting the hooks of the different arc shaped portions are disposed between adjacent converging webs of different grids so that the said oppositely extending flanges are just beneath the plane of the lower faces of the said adjacent converging webs. When then the said interlocking device is moved from its dotted line position in said Fig. 7 to its full line position therein, the oppositely extending flanges of the hooks slide beneath the end portions of the said adjacent converging webs which are closer together, while the ears of said hooks span the distance between the said adjacent webs. Thus, the interlocking device causes the different grids to be fastened together in vertical and horizontal alignment against the possibility of accidental displacement, as will be obvious.

Any other convenient type of interlocking device can be utilized. A device suitable for fastening together grids of the modified form of Fig. 12, where the webs bear either parallel or perpendicular relation to each other would, naturally, be of modified construction. In the instance of grids such as disclosed in said Fig. 12 it might be preferable to utilize an interlocking device of resilient nature and having hooks adapted to be sprung to position beneath the webs, or in either form of the invention it might be desirable in some cases to bolt or otherwise positively fasten adjacent or contiguous grids to each other.

While I have disclosed the cups 22 disposed in what may be called triangular (and square) spacings, it will be evident that other forms of spacings could be utilized. For

example, the cut-away portions between the different cups and webs could just as well be of general circular, elliptical, pentagonal, etc., conformation. In fact, the cut-away portions could even be of some irregular shape.

It may not be feasible in some instance to utilize downwardly extending projections or lips 23, as, for example, when a relatively thin slab of pavement or flooring is to be laid, but ordinarily it will be preferable to provide the said projections or lips to increase the vertical depth of the grid, and to provide for the maximum in bonding surface.

A steel grid constructed and imbedded, in the manner described, in any material suitable for floors or pavements, will form a permanently smooth wear-proof surface calculated to last indefinitely. For floors and pavements subjected to the action of the elements, copper-btaring corrosive-proof steel may be desirable. The size, thickness and spacing of the cups will be varied to suit different conditions.

The grid of the invention when constructed of steel and imbedded in a concrete or like slab will increase the strength of the slab and permit casting a thinner slab than would otherwise be required for a given load condition.

I preferably utilize a circular or other generally curved cup because such a form is superior to a rectangular, triangular, or any angular grid, chiefly because no sharp corners are present where the filler can probably break out quite easily. In case a part of the filler should break out, cups of continuous metal will withstand bending better than other types of grids, as for example, those formed of multiple bars which are interlocked, riveted, or welded together. The top edges of the cups will take all of the wear imparted to the floor or pavement, and being spaced apart and continuous, the cups will present no surfaces apt to cause slippage.

The provision of the webs spacing the cups apart, of the openings between the webs and cups, and of the downwardly projecting lips, as well as the provision of cups having open bottoms, furnishes a grid of reticulated structure to insure that the filler utilized will flow freely through and about the grid and become intimately contacted with all of the parts thereof, and that the grid will divide the various portions of the filler into relatively small quantities not calculated to become easily broken or cracked.

The improved grid can obviously be utilized in connection with floors and pavements of a great many different varieties not necessary to be here specifically mentioned.

Having thus fully described my invention, what I claim and desire to secure by Letters Patent of the United States, is:

1. A grid comprising a sheet metal base-plate adapted to be imbedded in filler material and having spaced apart filler receiving cups thereon, the upper edge faces of the said cups being disposed substantially in a single plane adapted to lie approximately flush with the surface of the said filler material above the elevation of said base-plate, and the bottoms of said cups being open.
- 5 2. A grid comprising a plurality of sheet metal filler receiving cups spaced apart by webs adapted to be imbedded in filler material, the said cups being up-struck from the plane of said webs and having their upper edge faces disposed substantially in a single plane, and projections down-struck from the plane of said webs.
- 10 3. A grid comprising a blank of sheet metal, a portion of which is formed into a plurality of filler receiving cups spaced apart by webs adapted to be imbedded in filler material, the said cups being up-struck from the plane of said webs and having their upper edge faces disposed substantially in a single plane, projections down-struck from the plane of said webs, and openings through the body of the blank of sheet metal between the cups and webs.
- 15 4. A grid comprising a blank of sheet metal, a portion of which is formed into a plurality of filler receiving cups spaced by webs adapted to be imbedded in filler material, the said cups being vertically up-struck from the plane of said webs and having their upper edge faces disposed substantially in a single plane adapted to lie approximately flush with the surface of the said filler material, projections vertically down-struck from the plane of said webs, and openings through the body of the blank of sheet metal between the cups and webs.
- 20 5. A grid comprising a blank of sheet metal, a portion of which is formed into a plurality of filler receiving cups, annular members about the bases of the cups and integral therewith, webs spacing said annular members apart and uniting the whole in an integral structure, the said webs and annular members being adapted to be imbedded in filler material, the said cups being up-struck from the plane of said annular members and having their upper edge faces disposed substantially in a single plane adapted to lie approximately flush with the surface of the said filler material above the elevation of said base-plate, projections down-struck from the plane of said webs, and openings through the body of the blank of sheet metal between the cups and webs.
- 25 6. The method of producing a grid from a blank of sheet metal, which consists in striking up spaced apart filler receiving cups from the body of said blank and disposing the free edge faces of said cups substantially in a single plane, and striking down projections from the body of said blank to situate said projections adjacent the face of the blank opposite said cups.
- 30 7. The method of producing a grid from a blank of sheet metal, which consists in striking up spaced apart filler receiving cups from the body of said blank and disposing the free edge faces of said cups substantially in a single plane, and cutting away portions of the body of said blank between said cups.
- 35 8. The method of producing a grid from a blank of sheet metal, which consists in striking up spaced apart filler receiving cups from the body of said blank and disposing the free edge faces of said cups substantially in a single plane, cutting away portions of the body of said blank between said cups, and striking down projections from the body of said blank to situate said projections adjacent the face of the blank opposite said cups.
- 40 9. The method of producing a grid from a blank of sheet metal, which consists in striking up spaced apart filler receiving cups from the body of said blank and disposing the free edge faces of said cups in a plane substantially parallel with said blank body, cutting away portions of the body of said blank between said cups to provide webs extending between the cups, and striking down projections from the body of said blank to situate said projections adjacent the face of the blank opposite said cups.
- 45 10. The method of producing a grid from a blank of sheet metal, which consists in striking up spaced apart filler receiving cups from the body of said blank, positively operating upon the free edge faces of said cups to dispose said free edge faces in a single plane, and striking down projections from the body of said blank to situate said projections adjacent the face of the blank opposite said cups.
- 50 11. The method of producing a grid from a blank of sheet metal, which consists in striking up spaced apart filler receiving cups from the body of said blank, positively operating upon the free edge faces of said cups to dispose them in a single plane, cutting away portions of the body of said blank between said cups, and striking down projections from the body of said blank to situate said projections adjacent the face of the blank opposite said cups.
- 55 12. The method of producing a grid from a blank of sheet metal, which consists in striking up spaced apart filler receiving cups from the body of said blank and disposing said cups perpendicularly of said blank body with their free edge faces substantially in a single plane, cutting away portions of the body of said blank between said cups, and striking down projections from the body of said blank to situate said projections adjacent the face of the blank opposite said cups.
- 60 130

13. A grid comprising sheet metal filler receiving cups spaced by webs and adapted to be imbedded in filler material, said cups being struck from the plane of said webs and having their upper edge faces disposed substantially in a single plane, and projections struck from the plane of said webs.

14. A non-skid pavement comprising a body portion having imbedded therein a plurality of cup shaped metal elements, the upper edges of which lie flush with the upper surface of said body portion, said cup shaped elements having webs at the base thereof to provide uniform spacing of the same and having projections struck from the base thereof.

15. A tread comprising a body portion having a plurality of interlocking grid-like sections firmly imbedded therein, each of said 20 grid sections comprising a plurality of filler receiving cups spaced apart by webs, the said cups being upstruck from the plane of the said webs and having their upper faces disposed substantially in a single plane 25 flush with the surface of the tread, and projections struck from the plane of said webs.

16. A grid of the character described comprising a base plate adapted to be imbedded in a filler material, spaced filler receiving cups 30 extending upwardly therefrom the upper edge faces of said cups being disposed substantially in a single plane adapted to lie approximately flush with the surface of said filler material, said base plate having openings therethrough between said filler receiving 35 cups.

17. A grid of the character described comprising a base plate adapted to be imbedded in a filler material, spaced filler receiving 40 cups extending upwardly therefrom, the upper edge faces of said cups being disposed substantially in a single plane adapted to lie approximately flush with the surface of the said filler material, said base plate having 45 openings therethrough between said filler receiving cups, and downwardly extending projections disposed below the level of said base plate.

18. A reenforcing and wear-resisting grid 50 for pavements and the like, comprising a sheet metal body and integral projections extending upwardly and downwardly from said body, said body having openings therethrough for receiving filler material.

55 19. A reenforcing and wear-resisting grid for pavements and the like, comprising a sheet metal base, and projections struck upwardly from said base and providing openings therethrough for said filler material, 60 said sheet metal base having openings therein between said projections.

20. A reenforcing and wear-resisting grid 65 for pavements and the like, comprising a sheet metal base having openings therein for receiving filler material, integral projections

extending upwardly from said base, and means for anchoring said base in the filler material of the pavement.

In testimony whereof, I have signed my name at Milwaukee, this 4th day of June, 70
1928.

EDWARD W. BURGESS..
